UNITED STATES PATENT OFFICE.

HENRY C. HERR AND HARVEY E. HERR, OF BUFFALO, NEW YORK, ASSIGNEES TO HERR MANUFACTURING CO. INC., OF BUFFALO, NEW YORK, A CORPORATION OF NEW YORK.

FLIER FOR SPINNING MACHINES.

Application filed July 23, 1923. Serial No. 653,082.

To all whom it may concern:

Be it known that we, HENRY C. HERR and HARVEY E. HERR, citizens of the United States, residing at Buffalo, in the county of Erie and State of New York, have invented new and useful Improvements in Fliers for Spinning Machines, of which the following is a specification.

This invention relates to improvements in the fliers employed in connection with spinning machines.

Its principal object is to provide a smooth running flier having a perfect bearing by which uniformity of tension and twist are obtained under all working conditions.

Another object of the invention is to provide a flier of this character which does not require the use of separate fastenings for retaining it on the spindle and which is readily applicable to all makes of spindles.

A further object is to provide a strong and durable flier in which the flier-block and its bearing are a self-contained unit capable of ready application and removal to and from the spindle.

A still further object of the invention is to provide simple and novel means for easily and quickly effecting the insertion and removal of the flier wires.

In the accompanying drawings:

Figure 1 is a fragmentary front view of a spinning machine showing our improved flier applied thereto. Figure 2 is a transverse vertical section on line 2—2, Fig.

3. Figure 3 is an enlarged front view of the flier in position on the spindle. Figure 4 is a top plan view thereof. Figure 5 is an enlarged vertical longitudinal section on line 5—5, Fig. 4. Figure 6 is an enlarged top plan view of the flier base and associated parts. Figure 7 is a cross section on line 7—7, Fig. 6. Figure 8 is a separated perspective view of the various parts forming the flier block. Figure 9 is a separated perspective view of the flier-base and locking ring. Figure 10 is a perspective view of one of the flier wires. Figure 11 is a top plan view of a flier showing a double-wire arrangement.

Similar characters of reference indicate corresponding parts throughout the several views.

The invention is shown in connection with a spinning machine of any well known con-

struction, and as illustrated particularly in Figs. 1 and 2, the same comprises a frame 10 upon which is mounted a series of upright spindles 11 for receiving the usual bobbins 12, the spindles being driven by a belt 13. The thread from each bobbin extends upwardly through guide-eyes 14, 15 and thence to a take-up spool 16 resting by gravity upon a horizontal driving pulley 17. Mounted on each spindle is the improved flier, designated generally by the numeral 18.

In its general organization, this flier consists of a bearing or flier-block which is revolvably mounted upon an anchoring sleeve or journal applied to the spindle, and a base plate or spider to which the flier wires are detachably connected, all parts of the device forming a self-contained unit preferably constructed of metal. The flier block is, by preference, in the form of a substantially hollow bearing consisting of a cup-shaped base-section 20 and an opposing similarly shaped top section 21 suitably fastened together, as by a lap or interlocking joint, shown at 22. Said sections are provided with alining central openings 23, 24, and surrounding these openings are inwardly-facing rims or thrust-collars 25, 26, whose opposing ends terminate short of each other to provide an intervening annular space or channel 27. These sections may be stamped from sheet metal and their jointed ends form an external head or shoulder 28 between the top and bottom of the flier block.

Loosely fitted within the openings 23, 24 of the flier-block is the anchoring sleeve or journal which preferably consists of a vertically-split band 29 of spring steel provided between its ends and on opposite sides thereof with external bosses or projections 30 forming thrust-bearings which are arranged between the thrust collars 25, 26 and permit a limited movement of the flier block lengthwise of its journal. The split band also constitutes the means by which the flier is anchored or frictionally held on the tapered end of the spindle 11, thus dispensing with separate fastenings for this purpose. The diameter of the openings 23, 24 is somewhat larger than the external diameter of the journal 29 in order to allow for the expansion of the latter as it is applied to the spindle and at the same time permit perfect

freedom of movement of the flier block both laterally and longitudinally relative to said journal.

The base plate or spider to which the flier wires or arms 31 are detachably connected is designated by the numeral 32. This base plate is provided with a central opening 33 which fits tightly over the lower block-section 20 below the bead 28. In its upper side 10 and at opposite ends thereof, the base plate is provided with wire-retaining loops or eyes 34 which may be formed by slitting said plate and punching the resulting portions between the slits upwardly, as shown in Figs. 7 and 9. The outer end of each flier wire is provided with the usual thread-engaging eye 35, while its inner end has a laterally offset or bent portion 36 arranged to lie flatwise on the base-plate between the flier 20 block and the opposing end of the respective retaining loop 34. For the purpose of securely and reliably holding the flier wire in this position, a locking device, preferably in the form of a rotatable ring or washer 37, 25 is provided which is interposed between the base plate and the external bead 28 of the flier-block. This locking ring may be carried directly by the base plate and held thereon by a retaining rim 38, as shown in Fig. 5. 30 At its diametrically opposite sides, said ring is provided with vertically offset projecting flanges 39 which overlap the bent-portions 36 of the flier-wires, said bent portions being confined between the vertical webs 40 of 35 said flanges and the opposing ends of the retaining loop 34, the bead of each wire abutting against the inner edge of its respective retaining loop.

In applying the flier wire 31 to the base 40 plate 32, the locking ring 37 is turned, by means of an appropriate tool, out of alignment with the loops 34, as shown by full lines in Fig. 6. The bent ends 36 of these wires are then threaded through the corresponding retaining loops, so as to extend 45 away from the companion locking flanges 39. The ring is now turned in the proper direction to simultaneously bring its locking flanges over the bent portions of the wires 31, by which action, the bent ends of the wires are sprung from the full-line to the dotted-line position shown in Fig. 6, by the advancing edges of the flange-webs, thereby 50 tightly locking the wires in position. To 55 remove the wires, the locking ring is turned back to its initial position to withdraw its flanges from engagement with the bent portions of the wires, which can then be readily detached from the base plate.

In Fig. 11 is shown the customary double-wire type of flier and the manner in which the several wires are locked in position through the medium of the locking ring 37.

This improved flier, while light in weight, is strong and durable in construction, it is

readily applicable to all makes of spindles and requires no separate fastenings for holding it in place. By mounting the flier block in the manner shown and described, there is no wear on the spindle, and the flier always 70 assumes the same position relative to the bobbin, thereby insuring uniformity of tension and twist under all working conditions.

It will be understood that this invention 75 may be incorporated in other forms than that shown in the drawings, and that various changes in the construction and arrangement thereof may be made within the spirit and scope of the appended claims.

By constructing the journal 29 in the form 80 of an expansive band, the flier is equally applicable to either the taper or straight type of spindle and its attachment thereto may be made at any point between the top of the spindle and the bobbin-head.

We claim as our invention:

1. A flier for spinning machines and the like, comprising a bearing-block for the flier-wires, and a journal for said block adapted for attachment to a bobbin-spindle. 90

2. A flier for spinning machines and the like comprising a journal adapted for attachment to a bobbin-spindle, and a flier-block mounted on said journal, said flier-block being laterally and longitudinally 95 movable relatively to said journal.

3. A flier-block for a bobbin-spindle, including a self-contained journal adapted to be detachably mounted on said spindle.

4. A flier-block for a bobbin-spindle, including an expansive journal member adapted to grip the spindle.

5. A flier-block for a bobbin-spindle, including a journal adapted for attachment to said spindle, said journal being constructed in the form of a split-sleeve. 105

6. A flier-block for a bobbin-spindle, including a journal having a thrust-bearing and adapted to be detachably mounted on said spindle. 110

7. A flier for spinning machines and the like, comprising a journal adapted for attachment to a bobbin-spindle, a flier-block loosely mounted on said journal, and means on said journal for limiting the endwise movement of the flier-block thereon. 115

8. A flier for spinning machines and the like, comprising a journal constructed in the form of a split-sleeve and adapted for attachment to a bobbin-spindle, a flier-block mounted on said journal, and means on said journal for limiting the endwise movement of the flier-block thereon. 120

9. A flier for spinning machines and the like, comprising a journal having a thrust-bearing and adapted for attachment to a bobbin-spindle, and a flier-block mounted on said journal and provided with thrust collars arranged on opposite sides of said thrust-bearing. 125

10. A flier for spinning machines and the like, comprising a journal constructed in the form of a split sleeve and adapted for attachment to a bobbin spindle, said sleeve being provided between its ends with external bosses, and a flier-block mounted on said journal and provided with oppositely-facing, thrust collars arranged for engagement with said journal bosses. 45
11. A flier for spinning machines and the like, comprising a journal having a thrust bearing and adapted for attachment to a bobbin-spindle, and a flier-block mounted on said journal and consisting of upper and lower bearing-sections having oppositely facing collars arranged to engage said thrust-bearing. 55
12. A flier comprising a hollow bearing-block having a central opening, and a journal-sleeve for said bearing block arranged in said opening, said bearing-block having a limited endwise movement on said journal sleeve. 60
13. A flier comprising a body having a wire-attaching base, and means for detachably connecting the flier-wires to said base. 70
14. A flier comprising a bearing block, a plurality of individual flier-wires mounted on said block, and unitary means for detachably securing the several flier-wires to said block. 75
15. A flier comprising a bearing-block having a wire-supporting member, a flier-wire mounted on said supporting member, and a rotatable locking device arranged to engage the inner portion of said wire for retaining the same in position. 80
16. A flier comprising a bearing block, a wire-supporting base carried thereby, a flier-wire mounted on said base, a locking member movably mounted on said supporting base and arranged to interlock with the inner portion of said flier-wire, said supporting base having holding means engag- 85
- ing the flier wire beyond said locking member. 45
17. A flier comprising a bearing-block, a wire-supporting base carried thereby, a flier-wire mounted on said base, the latter having a retaining loop through which the flier-wire passes, and a rotatable locking-ring arranged substantially centrally of said supporting base, the inner portion of said flier-wire being clamped between the locking ring and the opposing end of said retaining-loop. 55
18. A flier comprising a bearing-block, a wire-supporting base carried thereby, a flier-wire mounted on said base and having a bent inner end, said base having a retaining loop through which the flier-wire passes, and a rotatable locking ring arranged substantially centrally of said supporting base, said locking ring having an abutment face bearing against the bent end of the flier wire and an outwardly projecting flange overlapping said bent end. 65
19. A flier wire having a thread-engaging eye at its outer end and having its inner portion arranged at an obtuse angle to the body of the wire, the angularly disposed inner portion of the wire being adapted to be flatwise on the flier-body. 70
20. A flier comprising a supporting base, a flier wire, holding means on said base engaging said wire at a point between its ends, and means for deflecting the free inner portion of said wire laterally to retain it in said holding means. 75
21. The combination with a flier and a wire-holding device mounted thereon, of a flier-wire mounted on the flier and having its inner portion arranged at an obtuse angle to the body of the wire and resting flatwise on said flier for engagement with said holding means. 80
